RESERVATORY SUPPORTING DEVICE

Albert A. Baker and Harry L. Rhoades, Jr., Erie, Pa., assignors to Zurn Industries, Inc., Erie, Pa., a corporation of Pennsylvania

Application December 10, 1954, Serial No. 474,506

2 Claims. (Cl. 285—42)

This invention relates to roof sump adapters.

In previous roof drains wherein it was desired to install a drain in a new roof, it was necessary to provide a hole in the roof and to chamfer the top of the hole to provide a recess the thickness of the flange of the roof drain to be installed in order for the flange to nest therein. Further, with drains made according to prior designs, it was necessary to install the leader pipes to the reservoir before the roofing job was completed in order to hold the reservoir in place while the roofing was being installed. In this disclosure, a means is provided for installing the drain in the roof with the top flange of the reservoir flush with the roof without chamfering the edge of the hole in the roof to provide for thickness of the flange. Also, a means is provided for supporting the body of the drain on the roof before the leader pipes have been installed. The body is locked in place by means of an under deck clamp. This permits the roofer to install the body of the drain and complete the roofing job. At a later date, when the leader pipes have been installed, the hole is cut in the roofing material, the clamping collar is then installed, and the dome set in place.

More specifically, it is an object of this invention to provide a roof drain wherein the body of the drain can be installed in a plain cylindrical hole in a roof without the necessity of providing chamfered edges on the hole.

Another object of the invention is to provide a means for supporting the body of a roof drain independently of any leader pipes thereto prior to installation of piping.

Another object of this invention is to provide a roof drain which is simple in construction, economical to manufacture, and simple and efficient to use.

With the above and other objects in view, the present invention consists of the combination and arrangement of parts hereinafter more fully described, illustrated in the accompanying drawing and more particularly pointed out in the appended claims, it being understood that changes may be made in the form, size, proportions, and minor details of construction without departing from the spirit or sacrificing any of the advantages of the invention.

In the drawing:

Fig. 1 is a side view partly in cross section of the reservoir and adapter;

Fig. 2 is another view of the embodiment of the invention shown in Fig. 1; and

Figs. 3 and 4 show a bracket adapted to be substituted for the ring of Figs. 1 and 2.

Now with more specific reference to the drawing, Figs. 1 and 2 disclose a reservoir 201 having an inwardly extending rim 217 through which spaced threaded holes 218 are formed which are adapted to receive bolts which extend through spaced peripheral holes 200 in a clamping ring 221. The clamping ring 221 has a gravel retaining ledge 222 in which spaced peripheral grooves 223 are formed. Threaded apertures 260 in the form of blind holes are formed in the side of the reservoir 201

2

through which a threaded stud 261 is disposed. The head of the stud 261 extends through a slot 280 in the circular bracket 262 which has an upper flange 263 and a lower leg 264 thereon which extend outwardly from bracket 262 and are adapted to engage the upper surface 265 and the lower surface 266, respectively, of the roof.

The bracket members 262 could be made in the form of a ring but may be as shown in the form of spaced brackets for supporting the reservoir 201. A hoop member 270 may be attached to the bracket member 262 to form a partition along the edge of the hole 267 in the roof. The insulation material 268 can be put in place on top of the surface 265 and held in place against the hoop member 270 and the flashing 230 can be put in place thereover. Then, at any time thereafter, the reservoir 201 may be slipped through the hoop like partition member 270 from below into engagement with the flashing 230 and the studs 261 attached thereto to hold the strainer in place.

The studs 261 can be attached as shown in Fig. 1 and the clamping ring 221 can be put in place on top of the flashing 230 to hold it against the outwardly and upwardly curving surfaces 208. In this manner, it will be seen that the supporting brackets 262 can be put in place at any time during the construction of the building and the roof, including at a time after the installation of the flashing 230. Then, at any later convenient time, the reservoir 201 can be installed without any inconvenience to the procedure of installation. The leader pipes can then be installed to the outlet opening 281 of the reservoir 201 at any later date.

Fig. 3 shows a bracket having a body 301 and flanges 302 and 303 attached thereto at 303a and 304, respectively. The upper end 303 is adapted to be disposed in flush relation with the upper surface of a roof and the lower end 309 is adapted to be attached to a reservoir.

The foregoing specification sets forth the invention in its preferred practical forms but the structure shown is capable of modification within a range of equivalents without departing from the invention which is to be understood is broadly novel as is commensurate with the appended claims.

The embodiments of the invention in which an exclusive property or privilege is claimed are defined as follows:

1. In combination, a reservoir for a drainage system and means to attach said reservoir to a platform having a top and a bottom surface comprising a generally cup-shaped reservoir having generally vertical side walls, an open top, a bottom having an outlet therefrom, said outlet being adapted to be connected to a soil pipe, a hoop like partition member disposed around the outside upper portion of said side walls, circumferentially spaced clamping brackets disposed around the outside of the wall of said reservoir, the outside surface of said reservoir being disposed in engagement with the inside surface of said partition member and said brackets, said brackets being disposed below said partition member and having the inside walls of said brackets flush with the inside surface of said partition member, holes in said reservoir extending partly through the walls thereof, said clamping brackets each having a flat leg lying against the side of said reservoir, an upper and a lower vertically spaced, radially extending leg attached to each said flat leg, a slot in each said flat leg, a bolt extending through each said slot and threadably engaging said holes, said upper legs engaging the top of said platform and said lower legs engaging the bottom of said platform supporting said reservoir thereon, and an inwardly extending rim having an inwardly and downwardly extending top surface integrally attached to the upper edge of said reservoir, and a clamping ring for clamping flashing to said rim.

2. In combination, a reservatory for a drainage system and means to attach said reservatory to a platform having a top and a bottom surface comprising a generally cup-shaped reservatory having generally vertical side walls, an open top, a bottom having an outlet therefrom, said outlet being adapted to be connected to a soil pipe, a hoop like partition member disposed around the outside upper portion of said side walls, a clamping bracket disposed on the outside of the vertical side wall of said reservatory, the outside surface of said reservatory wall engaging the inside surface of said bracket, said clamping bracket having a flat leg lying against the side of said reservatory, an upper and a lower vertically spaced, radially extending leg attached to said flat leg, a slot in said flat leg, a hole in said reservatory extending partly through the wall, a bolt extending through said slot and threadably engaging said hole, said upper leg engaging the top of said platform and said lower leg engaging the bottom of

15

5

said platform supporting said reservatory thereon, an inwardly extending rim having an inwardly and downwardly extending top surface integrally attached to the upper edge of said reservatory, and a clamping ring for clamping flashing to said rim.
